Inventor,
Elizabeth M. Lesser,
by J. H. Little, her Attorney

UNITED STATES PATENT OFFICE.

ELIZABETH M. LESSER, OF WARREN, PENNSYLVANIA.

FASTENING-EYE FOR GARMENTS.

SPECIFICATION forming part of Letters Patent No. 660,300, dated October 23, 1900.

Application filed April 14, 1900. Serial No. 12,798. (No model.)

To all whom it may concern:

Be it known that I, ELIZABETH M. LESSER, a citizen of the United States, residing at Warren, in the county of Warren and State of Pennsylvania, but temporarily residing at New York, in the county and State of New York, have invented certain new and useful Improvements in Fastening-Eyes for Garments, of which the following is a specification.

This invention relates to fastening-eyes for garments, and it has particular relation to an eye such as is involved in the class of hook-and-eye devices which are used as fastening means upon women's and children's garments.

The object of my invention is to provide a simple and improved device of this class which can be conveniently applied in operative position without sewing or separate means of attachment to the garment, which will be concealed in all its major portion (except the projecting end for fastening engagement) beneath the surface fabric of the garment, which can be conveniently removed or detached when desired by a simple movement, which will not disfigure or tear the garment, which will positively and effectively maintain its operative position, which will be sure and safe in operation, and which will furthermore possess advantages in point of inexpensiveness, effectiveness, and general efficiency.

In the drawings, Figure 1 is a front or face view showing my invention in operative position with relation to the dress fabric. Fig. 2 is a rear face view of the matter illustrated in Fig. 1. Fig. 3 is a detail perspective view of the device. Figs. 4 and 5 are detail sectional views of the device in operative position.

Corresponding parts in all figures are denoted by the same numerals of reference.

Referring to the drawings, 1 designates the improved fastening-eye device, 2 designates the facing or outer fabric of the garment, and 3 designates the inner fabric or lining.

The device is preferably formed of a single piece of wire bent into shape. It comprises a central portion 4, embodying a cross-bar, as at 5, from each end of which extends an arm 6. The arms or side members 6 are curved

rearwardly and downwardly and forwardly and upwardly with relation to the cross-bar 5 in a segmental curvature, as represented at 55 7, the front terminus of said segmental curves terminating at a point in front of the cross-bar 5 and on the same plane approximately, there remaining a space or opening, as at 8, between the front terminus of the segmental 60 or curved portion 7 of the arms or side members 6 and the cross-bar 5. In front of the terminus of the segmental or curved portion 7 of the arms or side members 6 the side members are curved or turned downwardly and 65 forwardly, as at 9, thus forming a "hump" or raised portion projecting upwardly in relation to the plane of the cross-bar 5 and at a point just in front of the latter, said hump or raised portion being designated at 10. 70

From the lower front terminus of the hump or raised portion 10 at the bottom of the curve 9 the arms or side members 6 are forwardly extended, preferably in a straightline, to form insertion-points, as at 11. Said terminal points 11 preferably extend on a plane slightly above the bottom of the segmental or curved portion 7. 75

In the practical construction of the device from a single piece of bent wire the side members or arms 6, with their curved portions 9, 80 10, and 11, are formed by the end parts of the wire, while the cross-bar 5 is formed by the central part of the wire. The terminal ends of the portions 11 are preferably sharpened or pointed, as at 12. 85

In the practical application or operation of my improved fastening-eye it is adapted to be inserted into position and securely maintain said position without sewing or the employment of any threads or other supplementary means. To adjust the device into position, it is only necessary to insert the pointed end portions 11 and 12 of the side members or arms 6 inwardly through both the surface 95 fabric 2 and lining 3 of the garment and force said members through both the portions 2 and 3 until the same rest within the rear part of the rear segmental or curved portion 7. The end parts 11 and 12 are then inserted inwardly again through the lining 3, but not through the surface fabric 2, and are forced through until the lining rests at the front part of the segmental or curved portion 7, 100

when the hump or raised portion 10 and insertion ends 11 will be in position between lining 3 and face fabric 2, while the only portion of the device exposed at the face of garment and projecting through the fabric 2 will be the cross-bar 5 and rear part of the segmental or curved portion 7 and the only part of the device exposed at the rear face of the lining 3 will be the bottom or middle part of the segmental or curved portion 7. The insertion and operative position and maintenance of the fastening-eye with relation to the face fabric 2 and lining 3 will be readily understood by reference to Figs. 4 and 5 of the drawings.

It will be noted that the device 1 will be firmly maintained in operative position when simply inserted in the fabric, as just above mentioned, but that it can be as readily detached, when desired, by simply reversing the insertion movement, and that when in its operative position the insertion-point portion 11 is safely housed between the face fabric and lining, and any liability of tearing or damage to the garment is thus obviated. When in operative position, accidental disengagement of the device from the garment is entirely precluded, inasmuch as the device has a double engagement with the lining, as indicated at 13 and 14, at the front and rear of the segmental or curved portion 7, and it is necessary to turn and move the device in a plurality of positions before it can be withdrawn from its engagement with the fabric. When the part of the device which projects at the face of the garment and comprises the cross-bar 5 is engaged by the hook or similar fastening means, as represented at 15 in Fig. 5, the strain is in a direct plane and is securely and effectively met by the resistance of the fabric in its engaged connections with the side members or arms 6 of the device. The adjacent position of the cross-bar 5 and the humps or raised portions 10, which are intermediately between the rear segmental or curved portions 7 and the front insertion portions 11 provides for the safe retention of the engagement hook or member 15 down within the socket formed by the segmental or curved portion 7 and the cross-bar 5, which engagement is enhanced by the fact that the face fabric 2 will be "pinched" down in said socket between the cross-bar 5 and the humps or raised portions 10, which are contained between the face fabric and lining.

It will be noted that in the construction of the device as hereinabove described it comprises as its main elements the rear socket, formed by the segmental or curved portions 7 and the cross-bar 5, which socket is only partially exposed at the front or face of the garment, the middle or intermediate humps or raised portions, which project with relation to the mouth of said socket and form the front part of the latter, and the insertion portions or ends, which project forwardly from said intermediate raised portions, the inter-

mediate raised portions and insertion portions being inclosed between the face fabric 2 and the lining 3.

By a manifest and simple variation in the curvature of the cross-bar 5 to produce a hook in any adapted or ordinary form it is obvious that the device will provide a fastening-hook in lieu of a fastening-eye, which hook device can be applied to garments without sewing in the same manner as the eye form of the device, as hereinbefore described, and which will effectively operate in connection with said herein-described improved eye device or with any usual or ordinary fastening-eye device upon garments.

In the engagement of the rear socket portion of the eye device 1 by a hook device 15 the hook will engage the cross-bar 5 intermediately between the side members 6 7 and "pinch" the fabric down in said socket and between the humps or raised portions 10, as represented in Fig. 5, thus insuring the safe retention of the engagement between the hook and eye.

The operation and advantages of my invention will be readily understood by those skilled in the art to which it appertains and from the foregoing description and explanation. The device is exceedingly simple and is adapted for quick and convenient application, and it is adapted by reason of its improved contour or structure to operate with maximum efficiency and effectiveness.

I do not restrict myself to the precise details of construction and arrangement as herein shown and described, as it is manifest that various modifications may be made in the details of structure without departing from the spirit of my invention. I therefore reserve the right to all such variation or modification as properly falls within the scope of my invention and improvements and terms of the following claims.

Having thus described my invention, I claim and desire to secure by Letters Patent—

1. An improved fastening device of the class described, comprising a rear socket embodying a cross-bar or engaging member, an intermediate hump or raised portion projecting with relation to the mouth of said socket, and a front insertion portion extending forwardly from said intermediate raised portion, substantially as and for the purpose set forth.

2. An improved fastening device of the class described, comprising a rear socket embodying segmental or curved portions and a cross-bar or engaging member, intermediate humps or raised portions which project with relation to the mouth of said socket and form the front part of the latter, and insertion portions or ends extending forwardly from said intermediate raised portions, substantially as and for the purpose set forth.

3. An improved fastening device of the class described, formed of a single piece of wire bent to provide a rear socket portion em-

bodying a cross-bar or engaging means, an intermediate hump or raised portion projecting with relation to the mouth of said socket portion, and insertion portions or ends extending forwardly from said intermediate raised portion, substantially as and for the purpose set forth.

4. An improved fastening device of the class described, formed of a single piece of bent wire and comprising a socket portion embodying the segmental or curved sides connected at the top by a cross-bar or engaging member, the upwardly and downwardly curved intermediate humps or raised portions projecting at their apex with relation to the mouth of said socket portion, and the insertion portions or ends extended from said curved intermediate raised portions, substantially as and for the purpose set forth.

5. An improved fastening device of the class described, comprising a rear socket portion embodying a cross-bar or engaging member from the ends of which project segmental or curved portions forming side members, a middle or intermediate curved portion comprised in said side portions and projecting with relation to the mouth of said socket portion, and a front portion extended from said intermediate portion and forming an insertion means whereby the device may be inserted into position through the fabric of the garment.

6. An improved fastening device of the class described, comprising a segmental or curved socket portion, embodying a cross-bar

or engaging member from the ends of which extend curved side members which are continued to form a curved or humped intermediate portion projecting with relation to the mouth of said socket portion, the side members being extended from said intermediate portion to form insertion ends, substantially as and for the purpose set forth.

7. The combination, with the face or outer fabric and the lining of a garment, of a fastening device insertible within said fabrics and comprising a segmental or curved socket portion embodying a cross-bar or engaging member and curved side members, said curved side members passing through both the face and lining fabrics and the upper part of said socket portion being exposed at the face of the front or face fabric, a hump or raised portion comprised in the side members of the device and inclosed between the face fabric and the lining, the lining being engaged with said hump or raised portion and the latter being arranged to project with relation to the mouth of the front socket portion, and insertion ends comprised in the side members of the device and extending from the intermediate humped portion and inclosed between the face and lining fabrics.

In testimony whereof I have signed my name in the presence of the subscribing witnesses.

ELIZABETH M. LESSER.
